UNITED STATES PATENT OFFICE.

RALPH E. HEISEL, OF CHILlicothe, OHIO, ASSIGNOR TO THE MEAD PULP & PAPER COMPANY, OF DAYTON, OHIO, A CORPORATION OF OHIO.

PAPER-MAKING APPARATUS.

Application filed November 12, 1925. Serial No. 68,581.

This invention relates to paper-making machinery, and more particularly to that portion of paper-making machinery which has to do with the feeding of the paper-making stock upon the forming part of the machine.

One of the principal objects of the invention is to provide an inlet which is constructed for easy adjustment to give suitable control of the flow of the stock from the flow box to the forming wire.

Another object is to provide as a unitary structure a block member or closure adapted to be engaged in the opening of the inlet to control the width thereof.

Other objects of the invention will be apparent from the following description when taken in connection with the accompanying drawing, in which:

Fig. 1 is a fragmentary elevational view of an inlet incorporating the present invention;

Fig. 2 is a vertical section taken on the line 2—2 of Fig. 1; and

Fig. 3 is a section taken on the line 3—3 of Fig. 2.

Referring to drawing, the reference characters 20 and 21 designate respectively the flow-directing apron and the top plate of an inlet of the type shown in the co-pending application of Ralph E. Heisel, Serial No. 15,017, filed March 12, 1925. The flow-directing apron and top plate, as shown, form parts of an inlet of the well-known Voith type, the top plate 21 being movably connected to the front of the flow box, in the well-known manner. One end member of the flow box is indicated by the numeral 23, and carries a lug 24 which receives the adjusting bolts 43 described below. As is well understood in the art, these parts are connected with a flow box containing pulp or other fibrous material suspended in water, and constitute the orifice through which the pulp or paper-forming stock flows onto the forming wire 16 passing underneath the front edge of the flow-directing apron, which edge is shown at the left of Fig. 2. As is usual in inlet constructions of this character the top plate 21 is movably connected, or hinged, so as to swing up or down to adjust the effective height of the opening or orifice between the apron 20 and the front edge of the plate 21. Any suitable means may be provided for adjusting the top plate

21, such for example as the adjusting rods 22.

Means should be provided for closing the opening between the apron 20 and top plate 21, at the ends to prevent escape of the paper-forming stock except through the effective opening at the front edge of the plate 21, and this means is preferably made adjustable as at times it is desirable to vary the width of the inlet, and for this purpose I have provided a unitary block member or closure which may be received and held between the flow-directing apron 20 and the top-plate 21 of the inlet. This block member is so arranged and constructed that it may be adjusted to vary the width of the inlet opening without necessitating disassembling or rearrangement of the parts of the inlet or affecting adjustment thereof.

The block member or closure consists of top and bottom plates 25 and 26 which are adapted to lie against the opposed faces of the inlet top-plate 21 and the flow-directing apron 20 respectively, as best shown in Fig. 2. The top-plate 25 is provided at its forward edge with an upturned flange 27 adapted to engage the front edge of the inlet top-plate 21 to restrain any tendency for the top-plate 25 to slide rearwardly from the mouth of the inlet. The bottom plate is provided with a back plate 31 extending upwardly from the rear edge of the bottom plate 26 and formed or rigidly secured thereon, and is also provided at one end with a side plate 32 extending upwardly therefrom and preferably having its upper edge inclined at an angle approximating the general angle of setting of the top plate 21 during operation. The back plate 31 and the side plate 32 are held spaced from the top plate 25 so as to permit movement of the top plate toward or from the bottom plate and the back and end walls thereof as the member 21 is moved to vary the effective opening of the inlet. The top plate 25 is connected to the back plate 31 as well as the side plate 32 and the gap between these members is closed by means of rubber or other flexible material 33, the construction being such that the back plate 31 and flexible material 33 constitute a back wall for bridging the space between the apron 20 and inlet top-plate 21 to intercept the flow of the paper stock. The side plate 32 constitutes the lateral limiting wall of the inlet opening through which the paper

stock flows onto the forming wire. The flexible material 33 is connected with the plates 25, 31 and 32 in any suitable manner, as for example by clamping which may be 5 accomplished through the agency of the various clamping strips or plates 35, 36 and 37, connected to the plates in any suitable manner.

The block or closure may be positioned in 10 the inlet by inserting it between the flow-directing apron 20 and the top plate 21 at the one end of the inlet, the top plate 25 having first been compressed toward the bottom plate 26 to permit entry of the block 15 within the space available. The block or closure may be then slid along the inlet to vary the width of the inlet opening as desired. In order that the upper and lower plates 25 and 26 may be moved apart and 20 into contact with the upper and lower members of the inlet, springs 40 having their ends positioned over restraining bosses 41, are provided which are under such tension as to urge the members 25 and 26 apart 25 during all adjustments of the inlet. And the construction and arrangement of the parts, and the compression of the springs 40 is sufficient to frictionally hold the block in adjusted position within the inlet. However, in some cases it may be desirable to 30 rigidly secure the block in position, and for this purpose I have provided the back plate 31 with a slot 42 which is adapted to receive a bolt 43 by which the block may be rigidly 35 clamped against the edge of the flow box.

An important advantage of the present invention resides in the fact that this block may be quickly and easily placed in position, and that it may be readily adjusted to inlets 40 of various heights, variation in height being taken up by the compression springs 40 and the flexible wall material 33. Although the block has been illustrated in association with but one end of the inlet, it is obvious that 45 through a suitable reversal of parts it may also be applied to the other end of the inlet, or that it might even be placed at points intermediate the ends of the inlet so as to subdivide the inlet into a plurality of orifices 50 each flowing paper stock upon the forming wire to form a plurality of sheets of paper from a single inlet.

While the form of apparatus herein described constitutes a preferred embodiment 55 of the invention, it is to be understood that the invention is not limited to this precise form of apparatus, and that changes may be made therein without departing from the scope of the invention which is defined 60 in the appended claims.

What is claimed is:

1. In an inlet for paper-making machinery comprising a flow-directing apron and a plate controlling the effective height of 65 the inlet opening, means for varying the

width of said inlet opening comprising an expansible member adapted to be received between said apron and plate and to close off a portion of said inlet opening.

2. In an inlet for paper-making machinery 70 comprising a flow-directing apron and a plate controlling the height of the inlet opening, means for varying the width of said inlet opening comprising an expansible member adapted to be received between said 75 apron and plate and to close off a portion of said inlet opening, said expansible member being adjustable along the length of said apron and said plate to vary the width of said outlet opening.

3. In an inlet for paper-making machinery comprising a flow-directing apron and a plate controlling the height of the inlet opening, means for varying the width of said inlet opening, said means comprising 85 a block member adapted to be frictionally held between said apron and said plate to limit the width of said inlet.

4. In an inlet for paper-making machinery 90 comprising a flow-directing apron and a plate controlling the height of the inlet opening, means for varying the width of said inlet opening, said means comprising a wedge-shaped block adapted to be received between said apron and said plate.

5. In an inlet for paper-making machinery comprising a flow-directing apron and a plate controlling the height of the inlet opening, means for closing off a portion of 100 said inlet opening comprising a back wall for bridging the space between the apron and the top plate of the inlet to intercept the flow of paper stock, and yielding means adapted to engage the inlet to retain said back wall in position.

6. In an inlet for paper-making machinery comprising a flow-directing apron and a plate controlling the height of the inlet opening, means for closing off a portion of 110 said inlet opening comprising a back wall for bridging the space between the apron and the top plate of the inlet to intercept the flow of paper stock, and means engaged between the opposite faces of the apron and the top plate to hold said back wall in position.

7. In an inlet for paper-making machinery comprising a flow-directing apron and a plate controlling the height of the inlet opening, means for closing off a portion of 120 said inlet opening comprising a back wall for bridging the space between the apron and the top plate of the inlet to intercept the flow of paper stock, and means engaged between the opposite faces of the apron and the top plate to hold said back wall in position, said last mentioned means comprising 125 a bottom member rigidly connected with the back plate and a top member flexibly connected therewith.

8. In an inlet for paper-making machinery comprising a flow-directing apron and a plate controlling the height of the inlet opening, means for closing off a portion of said inlet opening comprising top and bottom plates adapted to engage respectively the top plate and the apron of the inlet, back and side plates rigidly connected with one of said first mentioned plates, and flexible means for closing the gap between said back and side plates and said other of the first mentioned plates.
- 5 In testimony whereof I hereto affix my signature.

RALPH E. HEISEL.
